DESIGN FOR A VANITY CASE

Frank McIntosh, New York, N. Y., assignor to Letheric Incorporated, New York, N. Y., a corporation of New York

Application July 1, 1938, Serial No. 78,205

Term of patent 7 years

To all whom it may concern:

Be it known that I, Frank McIntosh, a citizen of the United States, residing at New York city, in the county of New York and State of New York, have invented a new, original, and ornamental Design for a Vanity Case, of which the following is a specification, reference being had to the accompanying drawing, forming part thereof.

In the drawing:

Fig. 1 is a top plan view of a vanity case embodying my new design;

Fig. 2 is a front elevation thereof;

Fig. 3 is a bottom plan view thereof; and

Fig. 4 is an end elevation thereof.

I claim:

The ornamental design for a vanity case, substantially as shown.

FRANK McINTOSH.
